B. T. STEBER

LOOM

Filed Dec. 16, 1924

Inventor

BERNARD T. STEBER

By Edgar M. Kitchin
his Attorney.

UNITED STATES PATENT OFFICE.

BERNARD T. STEBER, OF UTICA, NEW YORK.

LOOM.

Application filed December 16, 1924. Serial No. 756,218.

To all whom it may concern:

Be it known that I, BERNARD T. STEBER, a citizen of the United States, residing at Utica, in the county of Oneida and State of New York, have invented certain new and useful Improvements in Looms; and I do hereby declare the following to be a full, clear, and exact description of the invention, such as will enable others skilled in the art 10 to which it appertains to make and use the same.

This invention relates to improvements in hand looms, and more particularly to the beater mechanism thereof.

15 An object in view is the production of an effective beater susceptible of and adapted for providing a track or runway for the shuttle while in the lowered or non-stroke position.

20 With this and further objects in view as will in part hereinafter become apparent and in part be stated, the invention comprises certain novel constructions, combinations and arrangements of parts as subsequently 25 specified and claimed.

In the accompanying drawings,—

Figure 1 is a transverse, vertical section through a loom embodying the features of the present invention, the section being taken 30 on approximately the plane indicated by line 1—1 of Figure 2.

Figure 2 is a horizontal section there-through taken approximately on the plane indicated by line 2—2 of Figure 1, and looking 35 downward, intermediate portions being broken out for indicating greater width than actually shown.

Figure 3 is a vertical, fragmentary section taken approximately on the plane indicated by line 3—3 of Figure 1.

40 Referring to the drawings by numerals, 1 indicates the frame of a hand loom, which, but for the beater mechanism, and its co-operating parts, may be of any ordinary type. Frame 1 includes side bars 2 between which a beater lever of bail-like form is 45 swung. This beater lever consists of arms 3, 3, pivoted at 4, 4, to the frame 1, the arms being rigidly connected at their ends opposite the pivots by a cross bar or hand 50 bar 5. The lever thus formed lies below the apex of the warp shed and above the heddles which are of ordinary construction and are not illustrated.

55 A reed frame 6, provided with the reeds 7, 7, between which the warp 8 is laced as

usual, is mounted on and fixed to or formed integral with end plates 9, 9, each pivoted at its rear end portion, as at 10, to the adjacent arm 3. Each plate 9 is arranged 60 above and in line with the respective side bar 2.

In operation, the reed-carrying frame or lever being in the position indicated in Figure 1, the shuttle is thrust across the loom 65 through the shed while resting on the upper edges of the reeds 7 which serve as a track. It is to be noted that when the track is in this position, it is perfectly horizontal. As soon as the shuttle has completed its stroke, 70 the reed frame is rapped upward by swinging the lever on the pivot 4, the bar 5 being employed as a hand bar for manually accomplishing this operation. In the starting 75 of this action, the arms 3 begin to rise on their pivots 4 while the end plates 9 begin to swing on their pivots 10 until the reed frame assumes a position parallel with the upper edges of the lever arms 3 in which position the reed frame will rest directly on 80 said arms and have the end plates 9 overhanging the arms at either side. The further upward movement of the lever brings the reeds 7 into the beating position against the weft which has just been laid. As the 85 shed is slightly inclined, the opposite inclination of the lever arms 3, when said arms are raised, will effect a position of the reeds 7 such that they will lie substantially at right angles to the warp at the juncture of 90 the shed with the woven fabric, thus affording the maximum beating efficiency. After the beating stroke has been completed, the lever is lowered, and as it descends, the front 95 or free ends of the plates 9 first engage the side bars 2 edgewise, and, thereupon said front ends cease to descend and begin a swinging movement on their pivots 10 until the plates 9 rest for practically their full length edgewise on the side bars 2. The 100 reed-carrying lever will be thus limited in its descent and supported in its lowermost position by the plates 9, and said plates at the same time will sustain the reed frame perfectly flat or horizontal, so that it is 105 again ready to receive the shuttle as a track therefor.

The invention herein claimed is illustrated but not claimed in my co-pending application Serial 756,219, filed December 16, 1924. 110

What is claimed is:—

1. In loom mechanism, the combination

with a loom frame, of a lever pivoted thereto, a reed movable relative to the lever located to be advanced by the lever to a weft-beating position substantially at right angles to the warp, and means for sustaining the reed in advance of the return location of the lever.

2. In loom mechanism, the combination, with a frame, of a lever pivoted thereto, a reed disposed in the path of the lever for being advanced by the lever to a weft-beating position, means for sustaining the reed in advance of the return location of the lever, and means for preventing dislocation of the reed relative to the lever longitudinally or transversely of the lever.

3. In loom mechanism, the combination, with a loom frame, of a beater lever pivoted thereto, and a reed frame pivotally connected to said lever substantially at that portion of the reed frame nearest the pivotal mounting of the lever for enabling the reed frame to swing from a beating position to a track-forming position for a shuttle.

4. In loom mechanism, the combination, with a frame, of a lever pivoted thereto, and a reed pivoted to the lever in position to move with the lever to the weft-beating position and located to be interrupted by a portion of the frame during the return movement of the lever to leave the reed in position to serve as a track for a shuttle.

5. In loom mechanism, the combination, with a frame, of a beater lever pivoted thereto, a reed having a frame extending across said lever andlapping the outer faces of the lever, the upper portions of the lever being adapted to strike the under face of the reed frame for elevating the same to the weft-beating position, means for preventing movement of the reed frame longitudinally of the lever, the reed frame being free to cease its return movement in advance of the final return location of the lever, and means for causing such cessation of the return movement of the reed frame.

6. In loom mechanism, the combination, with a frame, of a beater lever pivoted thereto, a reed having a frame extending across said lever in position to be struck by the upper portions of the lever for being elevated therewith to the weft-beating position, means for interrupting the return movement of the reed frame short of the re-

turn position of the lever, and a pivotal connection between the reed frame and the lever.

7. In loom mechanism, the combination, with a frame, of a beater lever pivoted thereto, a reed having a frame extending across said lever in position to be struck by the upper portions of the lever for being elevated therewith to the weft-beating position, means for interrupting the return movement of the reed frame short of the return position of the lever, and a pivotal connection between the end portions of the reed frame and the lever.

8. In loom mechanism, the combination, with a frame, of a beater lever pivoted thereto, a reed having a frame extending across said lever in position to be struck by the upper portions of the lever for being elevated therewith to the weft-beating position, means for interrupting the return movement of the reed frame short of the return position of the lever, and a pivotal connection between the rear parts of the end portions of the reed frame and the lever.

9. In loom mechanism, the combination, with a frame, of spaced lever arms pivoted to the frame, a hand bar connecting the arms, a reed frame extending across and above the arms, plates depending from the reed frame in position to lap the sides of the arms, a pivotal connection between said plates and said arms, and means for sustaining the reed frame in a horizontal position when said arms are in their lowermost inclined position.

10. In loom mechanism, the combination, with a frame, of spaced lever arms pivoted to the frame, a hand bar connecting the arms, a reed frame extending across and above the arms, plates depending from the reed frame in position to lap the sides of the arms, a pivotal connection between the rear ends of said plates and said arms, and means for sustaining the reed frame in a horizontal position when said arms are in their lowermost inclined position.

In testimony whereof I affix my signature in presence of two witnesses.

BERNARD T. STEBER.
